CLAIM

The ornamental design for display screen or portion thereof with animated graphical user interface, as shown and described.

DESCRIPTION

FIG. 1 is a front view of a first image in a sequence for a display screen or portion thereof with animated graphical user interface showing my new design;

FIG. 2 is a second image thereof;

FIG. 3 is a third image thereof;

FIG. 4 is a fourth image thereof;

FIG. 5 is a fifth image thereof; and,

FIG. 6 is a sixth image thereof.

The outermost broken line showing of the display screen and all other broken lines showing portions of the animated graphical user interface are included for the purpose of illustrating portions of the article and form no part of the claimed design. The appearance of the animated graphical user interface sequentially transitions between the images shown in FIGS. 1-6 according to an embodiment. The process or period in which one image transitions to another image forms no part of the claimed design.
